Application June 20, 1939, Serial No. 280,036

26 Claims. (Cl. 101—132.5)

This invention relates to duplicating machines of the liquid process type in which a master sheet is carried by a rotatably mounted drum and a copy sheet is carried into impression relationship with the master sheet at each revolution of the drum, and it has for its object the provision of a new and improved form and arrangement of parts by which a single line or some other fractional portion of the subject matter on the master sheet may be copied at each revolution of the drum, the arrangement preferably to be such that there may be a readjustment between each two revolutions of the drum so as to produce different copy for each copy sheet in turn.

In the preferred embodiment of this improved machine, means is provided for tucking the master sheet into an opening in the drum in the form of a loop and for progressively shifting the end portion of the master sheet so as to vary the length of the loop and to change the portion of the master sheet at the printing point adjacent to the mouth of the opening in the drum. For accomplishing this result, a roller is provided adapted to be moved inwardly in engagement with the outer face of a master sheet for pressing the master sheet into the opening and into pressure relationship with a forwarding roller rotatably mounted within the drum, means being provided for giving said forwarding roller a rotary movement at a predetermined point in each revolution of the drum for shifting the loose end portion of the master sheet. In the arrangement shown, the actuation of the forwarding roller is effected through the medium of a cam adapted to give an outward movement to a slidably mounted pawl in position to engage a ratchet wheel connected with said forwarding roller.

For controlling the application of the master sheet to the drum and for forming the desired loop in the master sheet, cam means is employed by which suitable master sheet gripping means is first actuated for gripping the master sheet when it is placed in position on the drum and by which after the master sheet is firmly gripped the loop-forming roller is caused to move under control into operative position for producing the desired even loop in the master sheet.

In the arrangement shown, means is provided for moving the cams out of operative position when desired. Thus the operator is enabled to arrange for actuation of the gripping and loop-forming means at the time when a new master sheet is being applied into position and not during the normal operation of the machine thereafter, and is enabled to interrupt the normal se-

quence of operation of the forwarding roller so as to provide for as many copies as may be desired of any particular portion of the master sheet.

5 This invention comprises also an alternative form and arrangement of parts in which the operating means for actuating the roller by which the master sheet is tucked inwardly into the opening in the drum is connected up for operation in time relation with the gripper operating means of the type heretofore used in liquid process machines. The arrangement shown comprises a cam pivotally mounted in position alongside of a pivotally mounted cam employed for opening the grippers and moved into operative position by the same means, such cam being arranged for cooperation with a train of parts for moving the tucking roller outwardly against the action of a spring. The structure comprises also an added lever for controlling the position of another cam which when in its operative position serves at each revolution of the drum to cause a shifting of the master sheet for bringing a different portion of such master sheet into operative printing position.

The invention employs in addition a guard plate preferably of sheet metal removably mounted in position over the free end portion of the master sheet so as to protect such portion of the master sheet from direct contact with the platen roller. The invention includes also a bridging member for closing the opening in the face of the drum through which the master sheet is pressed in the form of a loop. In some cases, a bridging member is employed in the form of a comparatively heavy metal foil which is adapted to be mounted in position underneath the master sheet in cases where the machine is to be operated in the ordinary manner for making full length copies without the use of the master sheet shifting means.

40 It is another object of this invention to improve apparatus of this type in sundry details hereinafter pointed out. The preferred means by which the several objects of the invention have been accomplished are illustrated in the accompanying drawings, in which—

Fig. 1 is a side face view of the preferred form of machine embodying the invention as seen from the left in Fig. 3 but with the frame plate at the side of the machine removed;

Fig. 2 is an enlarged detail view, being largely a vertical sectional view through the moistening mechanism of the machine;

Fig. 3 is a vertical sectional view taken sub-

stantially at the line 3—3 of Fig. 4, or taken on an enlarged scale at the line 3—3 of Fig. 1;

Figs. 4 and 5 are vertical sectional views taken substantially at the line 4—4 and the line 5—5, respectively, of Fig. 3, but with some of the parts in changed position;

Fig. 6 is a view similar to a portion of Fig. 4 but showing a changed position of the parts;

Fig. 7 is a top plan view of a modified form of machine with some parts shown in section;

Figs. 8 and 9 are vertical sectional views taken substantially at the line 8—8 and the line 9—9, respectively, of Fig. 7;

Fig. 10 is a vertical sectional view similar to a portion of Fig. 8 but with certain of the parts removed and with the operating levers and cams in changed position;

Fig. 11 is a vertical sectional view taken substantially at the line 11—11 of Fig. 7;

Fig. 12 is a view similar to Fig. 11 but with the parts in changed position and with an extra guard plate applied;

Fig. 13 is a top plan view of the machine as seen in Fig. 12 but on a smaller scale; and

Fig. 14 is a view similar to a portion of Fig. 11 but with some of the parts omitted and with a supporting metal foil plate underneath the master sheet.

Referring now to Figs. 1 to 6 of the drawings, 20 and 21 indicate standards formed of sheet metal pressed into dished form mounted in spaced relation at opposite sides of the improved machine with a drum 22 rotatably mounted between the standards upon a heavy shaft 23. In the arrangement shown, the standards 20 and 21 are 35 reinforced by plates 24. The standards 20 and 21 are further braced with respect to each other by a transversely positioned sheet metal angle bar 25, as is best shown in Fig. 1. In the arrangement shown, the shaft 23 is provided with a gear 26 fixedly mounted thereon which meshes with a pinion 27 which receives power from any suitable source for rotating the drum 22.

Adjacent to the drum 22, I have provided two rotatably mounted rollers 28 and 29 between 45 which a copy sheet 30 is adapted to be fed forwardly (toward the right in Figs. 1 and 2). In the arrangement shown, a moistening mechanism 31 of any suitable type is provided comprising an absorbent pad 32 which extends into engagement 50 with the top forwarding roller 28 for applying a thin film of liquid solvent upon the face of such roller. In the arrangement shown, solvent is supplied to the moistening mechanism 31 through a flexible pipe 33 from a pump 34 which takes the 55 solvent from a container 35. An overflow pipe 36 connects the moistening mechanism 31 with the container 35 for returning surplus solvent to such container. In the arrangement shown, the pump 34 is operated by power from the drum 22 through the medium of a lever 37 pivotally mounted at 38 upon the framework, the lever 37 being connected directly with the plunger of the pump. The lever 37 is actuated by a cooperating arm or lever 39 pivoted on the same axis with the lever 37 and provided at its free end with a roller 40 engaging a cam 41 fixedly mounted upon the shaft 23. A spring 42 normally holds the arm or lever 39 moved to the limit of its motion toward the shaft 23. An arm 43 connected with the lever 37 is provided with a roller 44 on its free end engaging a cam 45 adjustably mounted in position by means of a supporting shaft 46. By an adjustment of the cam 45 about the axis 70 of the shaft 46 the length of the stroke of the

lever 37 downwardly is controlled for regulating the amount of solvent or other liquid delivered by the pump through the pipe 33.

At the front of the machine (at the left in Fig. 5), I have provided a tray or table 47 for supporting a pile of copy sheets in position to be fed into the bite of the rollers 28 and 29.

In the construction illustrated, the forwarding roller 28 is driven by power from the shaft 23 by means of a large gear 48 carried by the shaft 23 so as to drive an idler pinion 49 which in turn drives a pinion 50 carried by said roller. The arrangement is such that upon rotation of the drum 22 in counter clockwise direction in Fig. 1, the roller 28 is driven also in counter clockwise direction in said figure at the same surface speed. The cooperating forwarding roller 29 is driven in clockwise direction in said Fig. 1 by engagement with the roller 28 or with a copy sheet interposed between the rollers, as shown in Fig. 2.

A platen roller 51 is rotatably mounted in position to engage the face of the drum 22 for pressing a copy sheet into impression relationship with a master sheet carried by the drum as herein-after described. In the arrangement shown, the platen roller 51 is supported in position by means of bellcrank levers 52 at opposite sides of the machine, such levers 52 being adjustable by means of bolts 53 and cooperating means as shown in Fig. 1. A receiving tray 54 is mounted in position for receiving the copy sheets as they pass between the platen roller 51 and the drum 22.

As is clearly shown in Fig. 3, the drum comprises two end plates 55 and 56 rigidly mounted upon the shaft 23 and connected by a cylindrical wall portion 57 which is provided with an opening 58 therethrough at one side of the drum. Between the end plates 55 and 56, I have rotatably mounted a roller 59 spaced inwardly a short distance from the outer face of the drum, as is best shown in Fig. 5, such roller being mounted in position by means of a shaft 60. At a short distance in advance of the roller 59, with respect to the direction of rotation of the drum 22 as indicated by the arrow in Fig. 4, I have pivotally mounted the arms 61 and 62 of a heavy yoke upon which a roller 63 is journaled, as is best shown in Fig. 4, the roller 63 in the arrangement shown being positioned in fairly close proximity to the cross bar portion 64 of the yoke. The arrangement is such that when the arms 61 and 62 are moved inwardly, the roller 63 is carried into and through the opening 58 in the drum so as to be brought into pressure relationship to the roller 59 within the drum. A coiled spring 65 normally holds the yoke moved inwardly to the limit of its motion, as shown in Fig. 5.

At a short distance in advance of the yoke upon which the roller 63 is mounted, I have provided another opening 66 through the wall of the drum, as shown in Fig. 4, within which a gripper bar 67 is adapted to fit, as shown in Fig. 5, for holding one end of a master sheet 68 in position on the drum. In the arrangement shown, the gripper bar 67 is provided with inwardly extending arms 69 which are slidably mounted with respect to the drum, being normally held in their operative gripping position as shown in Fig. 5 by means of coiled springs 70 connected with said arms, as shown in Figs. 3 and 4.

Upon one end of the shaft 60 of the roller 59, I have fixedly mounted a ratchet wheel 71. Adjacent to the ratchet wheel upon the outer face

of the end plate 56 of the drum, I have provided a slide bar 72 which is slidably mounted within a sleeve 73, a coiled spring 74 serving normally to hold the slide 72 at the innermost limit of its movement. Upon the slide 72, I have pivotally mounted a pawl 75 in position to engage the ratchet wheel 71, the pawl 75 being normally pressed by a flat spring 76 into engagement with the ratchet wheel.

For effecting automatic control of the gripper bar 67 and the tucking roller 63, and for automatically effecting rotary movements of the roller 59 in the desired timed relation, I have provided cam means 77 and 78, as shown in Fig. 4. The cam member 77 is slidable laterally of the machine upon pins or rods 79 which are slidable longitudinally within suitable openings in the framework of the machine, being provided with a cross bar 80 on their outer end portions for enabling them to be moved readily for carrying the cam 77 into and out of operative position. The cam 77 in its operative position as shown in solid lines in Fig. 3, is located in the path of a roller 81 carried by the arm 62 of the yoke upon which the roller 63 is mounted. In such operative position, the cam 77 is also in the path of a roller 82 carried by an arm 83 in position to engage the arms 69 upon which the gripper bar 67 is mounted. The cam 78 is likewise slidably mounted with respect to the drum, being supported by pins or rods 84 slidably mounted in the framework and provided with a connecting bar 85 on their outer ends for ready manipulation of the cam. When the cam 78 is in its operative position as shown in solid lines in Fig. 3, it is in the path of a roller 86 carried by the slide 72 upon which the pawl 75 is mounted.

With the cams 77 and 78 moved to their innermost positions as shown in solid lines in Fig. 3, and with the parts in the position as shown in Fig. 4, the roller 63 is held by the roller 81 and the cam 77 at the limit of its outward movement. With the parts in this position, a master sheet 68 is inserted in position upon the drum between the rollers 59 and 63, with its forward edge in engagement with the gripper bar 67 which is being held at the same time by the roller 82 and the cam 77 in opened position. When the drum 22 has been rotated a short distance in clockwise direction from the arrangement as shown in Fig. 4 to that shown in Fig. 6, the roller 82 is carried out of effective engagement with the cam 77 so as to permit the springs 70 to carry the gripper bar 67 inwardly to operative position for gripping the leading edge of the master sheet 68. When the drum has been moved still further in clockwise direction from the position as shown in Fig. 6, the roller 81 is adapted to pass out of engagement with the cam 77 so as to permit the spring 85 to carry the roller 63 inwardly through the opening 58 so as to bring the roller 63 into pressure relationship with the roller 59, but with the master sheet 68 interposed between the rollers, the master sheet 68 being pressed inwardly ahead of the roller 63 into the form of a loop. After this result has been effected, the cam 77 is ordinarily moved outwardly (toward the right in Fig. 3) into the position as shown by dotted lines in said Fig. 3 so that upon the next succeeding revolution of the drum the cam 77 shall pass the rollers 81 and 82 without in any way affecting the position of the tucking roller 63 or the gripper bar 67.

When the drum upon continued rotation in clockwise direction in Fig. 4 brings the roller 86

into engagement with the cam 78, the slide 72 and the pawl 75 are moved outwardly so as to cause the roller 59 to have a limited rotation in clockwise direction in Fig. 4. Such clockwise rotation of the roller 59 serves to move the engaged portion of the master sheet 68 toward the right in Figs. 4 and 5, inasmuch as the master sheet is under such circumstances effectively gripped between the rollers 59 and 63. This results in a slight increase in the size of the loop formed in the master sheet 68, the arrangement preferably being such that the master sheet is shifted through a distance corresponding to the spacing between lines of copy on the sheet. As will be readily understood, upon each succeeding revolution of the drum 22 the master sheet 68 is shifted an additional step toward the right in Fig. 5 for progressively increasing the size of the looped portion of the sheet.

In the use of the machine as above described, the copy sheets are fed one at a time to the forwarding rollers 28 and 29 by which said sheets are aligned for assuring that the copy from the master sheet shall be aligned accurately across the copy sheet. The master sheet is so arranged that the leading margin is bare and arranged so that the first line of subject matter to be copied from the master sheet is positioned initially at a point immediately at the left of the bar 84 of the tucking roller arrangement as shown in Fig. 5. The arrangement is such that the rear edge portion of the copy sheet is brought into impression relationship with the line of subject matter on the master sheet next adjacent to the opening 58. The result is that upon the first operation of the machine following the application of a new master sheet, the leading line of subject matter on the master sheet is printed upon the bottom line portion of the first copy sheet presented; upon the second rotation of the drum the second line of copy on the master sheet is printed on the bottom line portion of the second copy sheet,—such successive printing of different lines upon different copy sheets continuing until the master sheet has been shifted sufficiently for bringing the last line of copy thereon into the printing position. In case it should be desired that a plurality of copy sheets be made with respect to any one or more of the lines of copy on the master sheet, this result is attained by a timely movement of the cam 78 out of operative position so as to interrupt temporarily the normal sequence of operations.

When a new master sheet is to be applied to the drum in place of an old master sheet, the cam 77 is moved into operative position as shown in solid lines in Fig. 3. When the parts reach the position then as shown in Fig. 4, the old master sheet can be removed manually from the drum and a new master sheet can be placed in position corresponding to the arrangement as shown in Fig. 4.

In the construction as shown in Figs. 7 to 14 inclusive, the arrangement is in effect very much the same as that above described. The arrangement is however modified with respect to many of the details for adapting the invention to a well-known form of machine.

In the arrangement as shown in Figs. 7, 8 and 9, the framework 87 of the machine supports a drum 88 rotatably mounted in position upon a shaft 89. Forwarding rollers 90 and 91 are provided (see Fig. 9) arranged for feeding copy sheets to the drum, such forwarding rollers being driven by means of a pinion 92, an idler pinion

99 and a gear 94 carried by the shaft 89, as shown in Fig. 8. The roller 90 is to be moistened with a suitable solvent preferably in the manner indicated in connection with the arrangement first described. A platen roller 95 is provided (see Fig. 8) for pressing a copy sheet into impression relationship with a master sheet mounted on the drum as hereinafter described.

In the arrangement shown, the drum 88 is provided with a plurality of grippers 96 mounted on a rock shaft 97 with coiled springs 98 and pins 99 holding the grippers in the desired operative position with respect to the shaft. For controlling the position of the shaft 97 and the grippers carried thereby, the shaft is provided with an arm 100 fixedly mounted thereon, having a roller 101 rotatably mounted on its free end portion for engagement with a cam as hereinafter described. A coiled spring 102 normally holds the arm 100 moved inwardly to the limit of its motion for holding the grippers closed, as shown in Fig. 11.

The cam provided as above suggested for cooperation with the roller 101 is indicated by the reference character 103, being pivotally mounted at its end portion, toward the right in Fig. 8, upon a pin 104 carried by a lug 105 extending from the framework of the machine. A coiled spring 106 engaging a pin 107 carried by the cam and a pin 108 extending from the framework holds the cam 103 normally turned to the limit of its motion in counterclockwise direction in Fig. 8. For controlling the position of the cam and for moving it outwardly against the action of the spring 106, I have provided a lever 109 pivotally mounted on the shaft 89, such lever being provided with a roller 110 rotatably mounted thereon in position to engage the bottom edge face of the cam. When the lever is given a movement in counterclockwise direction in Fig. 8, the roller 110 serves to force the cam upwardly into position for engagement with the roller 101, as shown in Fig. 10, for rocking the shaft 97 so as to cause the grippers 96 to open as shown in said figure, such action taking place at a predetermined point in each revolution of the drum 88. Inasmuch as the parts as above described in connection with Figs. 7 to 14 form in and of themselves no part of my present invention, it is believed to be unnecessary to describe their construction or operation further.

As is best shown in Fig. 11, the cylindrical wall portion of the drum 88 is provided with an opening 111 therethrough at a point a little in rear of the grippers 96 with reference to the counterclockwise direction of rotation of the drum in said figure. In the drum 88 directly opposite to the opening 111, there is a roller 112 rotatably mounted by means of a shaft 113 upon which the roller is fixedly mounted, such roller 112 being spaced at a short distance inwardly from the face of the drum. For supporting a tucking roller 114 movably in position opposite the roller 112, I have provided arms 115 and 116 slidably mounted on the end walls of the drum 65 at the ends of the roller 112, such arms being slidably between guides 117. Springs 118 serve normally to hold the arms 115 and 116 and the roller 114 at the limit of their movement inwardly, as shown in Fig. 12, with the roller 114 applying pressure inwardly on the roller 112.

Means is provided for moving the roller 114 outwardly against the action of the springs 118 in the position as shown in Fig. 11 with the roller 114 spaced outwardly from the face of the drum. 75

This means in the construction illustrated comprises arms 119 fixedly mounted on a shaft 120 journaled between the end walls of the drum 88, the arms 119 being in position to engage the inner ends of the arms 115 and 116 for applying pressure outwardly on such arms. For rocking the shaft 120, I have provided an arm 121 fixedly mounted thereon, having a roller 122 rotatably mounted upon its free end portion, such roller 122 being in position to engage the top edge face of a cam 123 rotatably mounted upon the pin 104 which supports the cam 103.

The arrangement of the tucking roller 114 and its associated parts is such that when the lever 109 is moved in counterclockwise direction in Fig. 8 to the position as indicated in Fig. 10, the cam 123 is raised by the action of the roller 110 into the position as shown in said Fig. 10. The arrangement is such that when the drum 88 rotates in counterclockwise direction in Fig. 10 with the remaining parts in the position as there shown, the grippers 96 are opened through the action of the cam 103 and the arms 121 and 119 are swung in counterclockwise direction by the action of the cam 123 upon the roller 122. The arrangement and timing of the parts are such that as the drum rotates in counterclockwise direction in Fig. 10, the roller 101 by engagement with the cam 103 serves to open the grippers and the roller 122 by engagement with the cam 123 serves to move the tucking roller 114 outwardly into the position as shown in Fig. 11. With the grippers 96 held in open position as shown in Fig. 10 and with the roller 114 held in outwardly retracted position as shown in Fig. 11, a master sheet 124 is placed in position on the face of the drum underneath the roller 114 with its forward edge engaged by the grippers 96. Upon the continued counterclockwise rotation of the drum in said Figs. 10 and 11, the grippers 96 are first closed under the control of the roller 101 and the cam 103, and the roller 114 is thereafter moved inwardly under the control of the roller 122 and the cam 123. As the roller 114 moves inwardly into engagement with the master sheet 124 whose forward edge is at that time gripped by the grippers 96, the master sheet is tucked through the opening 111 in the wall of the drum and is brought in the form of a loop into pressure relationship with the roller 112 so as to be movable by the cooperative action of the rollers 112 and 114. As is clearly shown in Fig. 11, the arms 115 and 116 are cut away at 125 for enabling the arms to extend past the shaft 113 of the roller 112.

For giving the roller 112 intermittent rotary movement upon successive revolutions of the drum 88, the shaft 113 of said roller is provided with a pinion 126 at the end portion of the shaft adjacent to the gear 94 (see Fig. 7). As is best shown in Fig. 9, a lever 127 is pivotally mounted on the drum adjacent to the pinion 126, being provided with a small roller 128 on its free end in position to engage between the teeth of the pinion 126, being normally pressed by a coiled spring 129 into engagement with the pinion so as to hold the pinion releasably in the desired critical position.

For rotating the pinion 126 in counterclockwise direction in Fig. 9, I have provided an arm 130 pivotally mounted on the shaft 113 provided with a pawl 131 pivotally mounted thereon so as to engage the teeth of such pinion 126. A coiled spring 132 is connected at one end with the arm 130 and is connected at its opposite end

with an arm 133 in the form of a cam as herein-after described, serving normally to swing the arm 130 to the limit of its motion in clockwise direction in said Fig. 9. A pin 134 mounted in the framework of the machine limits the clockwise movement of the arm 130 in said Fig. 9. As will be readily understood, when the arm 130 is given a swinging movement in counterclockwise direction in Fig. 9, the pinion 126 and the roller 112 are rotated in counterclockwise direction in said figure.

For giving the arm 130 a swinging movement at a predetermined point in each revolution of the drum 88, I have provided a lug 135 on the cam arm 133 extending past the edge of the arm 130 so that when the arm 133 is swung toward the left in Fig. 9 the arm 130 is caused to move also toward the left for producing a rotary movement of the pinion 126 and the connected roller 112.

For giving the cam arm 133 swinging movements inwardly upon successive revolutions of the drum, I have provided a cooperating cam plate 136 slidably mounted upon the framework of the machine by means of a pin 137 working in a slot 138 of the cam plate. For cooperation with the cam plate 136, I have provided an operating lever 139 pivotally mounted upon the framework adjacent to the cam plate and pivotally connected with said cam plate by means of a rivet 140 (see Fig. 9). At an intermediate point on the lever 139, I have pivotally connected a link 141 which extends thence upwardly, its upper end being pivotally connected with an arm 142 which is pivotally mounted upon a pin 143, a lever or handle 144 being connected with the arm 142 so as to swing therewith. The arrangement is such that when the lever 144 stands in upright position as shown in Fig. 8 the link 141 holds the arm 139 in turned position as shown in Fig. 8, such arm 139 in turn serving to hold the cam 136 projected toward the right in said Fig. 8 opposite the gear 94. When however the lever 144 is moved outwardly into the position as shown in Fig. 9, the arm 139 is swung outwardly for holding the cam plate 136 in outwardly shifted position. The arrangement is such that when the cam plate 136 stands in the position as shown in Fig. 8 it engages the cam arm 133 upon each revolution of the drum for forcing such cam arm 133 inwardly for causing a rotary movement of the roller 112. As is clearly shown in Fig. 8, the link 141 is adapted to pass centers with respect to the arms 139 and 142 so as to be effective for preventing retraction of the cam plate 136 except as the lever 144 is swung toward the left into the position as shown in Fig. 9.

In the use of the machine as above described, a master sheet 124 is applied in position upon the drum and promptly tucked through the opening 111. After the master sheet has been applied in position, the lever 109 is moved manually from the position as indicated in Fig. 10 to the position as shown in Fig. 8. Upon each revolution of the drum thereafter, with the lever 144 in the position as shown in Fig. 8, the master sheet 124 is shifted for progressively increasing the size of the loop, until the entire quota of subject matter has been copied from the master sheet upon a series of copy sheets. If it is desired that more than one copy be made of any particular line of the subject matter on the master sheet, the lever 144 is moved outwardly to the position as shown in Fig. 9 for retracting the cam plate 136 temporarily from operative

position. The arrangement preferably is such that the master sheet is moved at each actuation through a distance corresponding with the spacing between lines thereon.

5 In Fig. 12, I have shown a guard plate 145 preferably of sheet metal curved to conform to the face of the drum, such guard plate being removably secured in position upon the drum so as to cover the greater portion of that part of 10 the master sheet 124 in rear of the tucking roller 114. As is shown in Fig. 13, the master sheet is all covered at the right of the roller 114 except for the small portion at the normal printing position immediately adjacent to said roller. In 15 the arrangement shown, the guard plate is held in position by means of spring clips 146 carried by the drum at opposite ends thereof, as is best shown in said Fig. 13. By the use of the guard plate 145, the master sheet is protected from direct contact with the platen roller at the end portion of the master sheet beyond the bottom edge of the copy sheet. Inasmuch as the platen roller is kept dry at all times, the use of the guard plate is not essential, but the sharpness 20 of the copy on the master sheet is better preserved by the use of the guard.

In the arrangement shown in Fig. 14, I have shown a master sheet 147 secured upon the drum 88 together with a sheet 148 of metal foil, the 30 foil being secured in position with the master sheet by the grippers 96. The metal foil member 148 is for use when the machine is being used for general work without any shifting of the master sheet, the foil being employed for bridging the opening 111 so as to provide support for the master sheet at this point.

By the use of my improved construction, I am 40 enabled to produce a series of copy sheets each bearing a different copy from the remaining sheets. This expedient may be desired in connection with the production of pay checks from a master sheet in the form of a pay roll, or it may be used under any other suitable circumstances where such an arrangement may be desired. It will be understood that I prefer to 45 employ the form and arrangement of parts as shown in the drawings and as above described, but my invention is not to be limited thereto except so far as the claims may be so limited, 50 it being understood that changes might well be made in the form and the arrangement of parts without departing from my invention.

I claim:

1. In a duplicating machine, the combination 55 of a rotatably mounted drum having an opening through its wall along one side thereof, gripper means for securing one end of a master sheet on the outer face of said drum adjacent to said opening, a roller rotatably mounted in said drum opposite to said opening, means engaging an intermediate portion of said master sheet for pressing it firmly against said roller, and means adapted upon each revolution of said drum to give said roller a rotary movement for bringing a different portion of said master sheet into printing position on the outer face of the drum adjacent to said opening.

2. In a duplicating machine, the combination 70 of a rotatably mounted drum having an opening through its wall along one side thereof, gripper means for securing one end of a master sheet on said drum adjacent to said opening, a roller journaled in the end walls of said drum opposite to said opening, a second roller rotatably mounted on said drum so as to be movable toward and

from said first-named roller for pressing an intermediate portion of said master sheet into engagement with said first-named roller, and means adapted upon each revolution of said drum to give said first-named roller a rotary movement for bringing a different portion of said master sheet into printing position adjacent to said opening.

3. In a duplicating machine, the combination of a rotatably mounted drum having an opening through its wall along one side thereof, a roller rotatably mounted in said drum opposite to said opening, means for pressing a master sheet mounted on said drum through said opening in the form of a loop and into engagement with said roller, and means adapted upon each revolution of said drum to give said roller a rotary movement for bringing a different portion of said master sheet into printing position adjacent to said opening.

4. In a duplicating machine, the combination of a rotatably mounted drum having an opening through its wall along one side thereof, a roller rotatably mounted in said drum opposite to said opening, means adapted automatically upon rotary movement of the drum to press a master sheet mounted on the drum through said opening in the form of a loop and into engagement with said roller, and means adapted upon each revolution of the drum to give said roller a rotary movement for bringing a different portion of said master sheet into printing position adjacent to said opening.

5. In a duplicating machine, the combination of a rotatably mounted drum having an opening through its wall along one side thereof, a roller rotatably mounted in said drum opposite to said opening, a second roller movably mounted on said drum so as to move inwardly and outwardly through said opening adapted upon an inward movement to press a master sheet wrapped about the drum underneath said second roller through said opening in the form of a loop and into engagement with said first-named roller, and means adapted upon each revolution of the drum to give said first-named roller a rotary movement for bringing a different portion of said master sheet into printing position adjacent to said opening.

6. In a duplicating machine, the combination of a rotatably mounted drum having an opening through its wall along one side thereof, grippers movably mounted on said drum adjacent to said opening, a roller rotatably mounted in said drum opposite to said opening, a second roller rotatably mounted on said drum so as to be movable toward and from said first-named roller through said opening, means adapted upon a rotary movement of the drum to close said grippers for securing one end of a master sheet in position on the drum, means adapted thereafter upon a continued rotary movement of the drum to move said second roller inwardly for pressing said master sheet through said opening in the form of a loop and into engagement with said first-named roller, and means adapted upon each revolution of the drum to give said first-named roller a rotary movement for bringing a different portion of said master sheet into printing position adjacent to said opening.

7. In a duplicating machine, the combination of a rotatably mounted drum having an opening through its wall along one side thereof, grippers movably mounted on said drum adjacent to said opening, a roller rotatably mounted in said drum opposite to said opening, a second roller rotatably mounted on said drum so as to be movable toward and from said first-named roller through said opening, means comprising a cam movably mounted adjacent to said drum so as to be moved into and out of operative position adapted upon rotary movement of the drum with the cam in operative position to cause said grippers to close for securing one end of a master sheet in position on the drum and adapted thereafter upon continued rotation of the drum to move said second roller inwardly for pressing said master sheet through said opening in the form of a loop and into engagement with said first-named roller, and means adapted upon each revolution of the drum to give said first-named roller a rotary movement for bringing a different portion of said master sheet into printing position adjacent to said opening.

bly mounted on said drum so as to be movable toward and from said first-named roller through said opening, means comprising a cam movably mounted adjacent to said drum so as to be moved into and out of operative position adapted upon rotary movement of the drum with the cam in operative position to cause said grippers to close for securing one end of a master sheet in position on the drum and adapted thereafter upon continued rotation of the drum to move said second roller inwardly for pressing said master sheet through said opening in the form of a loop and into engagement with said first-named roller, and means adapted upon each revolution of the drum to give said first-named roller a rotary movement for bringing a different portion of said master sheet into printing position adjacent to said opening.

8. In a duplicating machine, the combination of a rotatably mounted drum having an opening through its wall along one side thereof, grippers movably mounted on said drum adjacent to said opening, a roller rotatably mounted in said drum opposite to said opening, a second roller rotatably mounted on said drum so as to be movable toward and from said first-named roller through said opening, means comprising a cam movably mounted adjacent to said drum so as to be moved into and out of operative position adapted upon rotary movement of the drum with the cam in operative position to cause said grippers to close for securing one end of a master sheet in position on the drum and adapted thereafter upon continued rotation of the drum to move said second roller inwardly for pressing said master sheet through said opening in the form of a loop and into engagement with said first-named roller, and means comprising a second cam movably mounted adjacent to said drum so as to be moved into and out of operative position adapted upon each revolution of the drum with the cam in operative position to give said first-named roller a rotary movement for bringing a different portion of said master sheet into printing position adjacent to said opening.

9. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable into and out of pressure relationship to said first-named roller adapted in one position to permit insertion of a master sheet between the rollers and adapted in the other position to cooperate with said first-named roller for gripping the master sheet for moving it with respect to the drum, and means adapted upon each revolution of the drum to give said rollers rotary movement for bringing a different portion of such gripped master sheet into printing position adjacent to said opening.

10. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable radially through said opening in the wall of the drum into engagement with said first-named roller or alternatively into outwardly spaced relation to the face of the drum for permitting the positioning of a master sheet on the face of the drum between said two rollers.

said second roller being adapted by an inward stroke with a master sheet in position on the drum between the rollers to press the master sheet into the form of a loop into effective engagement with said first-named roller, and means adapted upon each revolution of the drum to give said rollers rotary movement for bringing a different portion of said master sheet into printing position adjacent to said opening.

11. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable radially through said opening in the wall of the drum into engagement with said first-named roller or alternatively into outwardly spaced relation to the face of the drum for permitting the positioning of a master sheet on the face of the drum between said two rollers, operating means movable into and out of operative position adapted when in operative position to cause said second roller to move outwardly beyond the face of the drum when the drum is rotated for permitting a master sheet to be positioned on the face of the drum over said opening in the wall and adapted then upon continued rotation of the drum to move said second roller inwardly for pressing said master sheet into the form of a loop and into effective engagement with said first-named roller, and means adapted upon each revolution of the drum to give said rollers rotary movement for bringing a different portion of said master sheet into printing position adjacent to said opening.

12. In a duplicating machine, the combination of a rotatably mounted drum having an opening through its wall at one side thereof and extending substantially the full length of the drum, a roller rotatably mounted in said drum opposite to said opening and spaced inwardly a short distance from the face of the drum and extending substantially the full length of the drum, a second roller rotatably mounted in position adjacent to said first-named roller and extending substantially the full length of the drum and movable into and out of pressure relationship to said first-named roller for permitting the insertion of a full-width master sheet between the rollers in position to be gripped by the rollers, and means adapted upon each revolution of the drum to give said rollers rotary movement for bringing a different portion of such gripped master sheet into printing position adjacent to said opening.

13. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable into and out of pressure relationship to said first-named roller adapted in one position to permit insertion of a master sheet between the rollers and adapted in the other position to cooperate with said first-named roller for gripping the master sheet for moving it with respect to the drum, means adapted upon each revolution of the drum to give said rollers rotary movement for bringing a different portion of said gripped master sheet into printing position adjacent to said opening, and means serving when said second roller is in pres-

sure relationship to said first-named roller substantially to close said opening in the wall of the drum flush with the adjacent face portions of the drum.

14. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable radially through said opening in the wall of the drum into engagement with said first-named roller or alternatively into outwardly spaced relation to the face of the drum for permitting the positioning of a master sheet on the face of the drum between said two rollers, and a bar movable inwardly and outwardly with said second roller adapted when said second roller is in pressure relationship to said first-named roller substantially to close said opening in the wall of the drum flush with the adjacent face portions of the drum.

15. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable into and out of pressure relationship to said first-named roller adapted in one position to permit insertion of a master sheet between the rollers and adapted in the other position to cooperate with said first-named roller for gripping the master sheet for moving it with respect to the drum, a platen roller rotatably mounted adjacent to the drum so as to press a copy sheet against the master sheet carried by the drum, means adapted upon each revolution of the drum to give said rollers rotary movement for bringing a different portion of such gripped master sheet into printing position adjacent to said opening in the drum, and guard plate means removably mounted on the drum in slightly spaced relation to said opening circumferentially of the drum so as to cover a portion of said master sheet for holding the copy sheet and the platen roller out of engagement with the master sheet at points beyond the normal printing position.

16. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable into and out of pressure relationship to said first-named roller adapted in one position to permit insertion of a master sheet between the rollers and adapted in the other position to cooperate with said first-named roller for gripping the master sheet for moving it with respect to the drum, a platen roller rotatably mounted adjacent to the drum so as to press a copy sheet against the master sheet carried by the drum, means adapted upon each revolution of the drum to give said rollers rotary movement for bringing a different portion of such gripped master sheet into printing position adjacent to said opening in the drum, a curved guard plate of sheet metal covering a portion of said master sheet for holding the copy sheet and the platen roller out of engagement with the master

sheet at points beyond the normal printing position, and spring clips for holding said guard plate removably in position on the drum.

17. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable into and out of pressure relationship to said first-named roller adapted in one position to permit insertion of a master sheet between the rollers and adapted in the other position to cooperate with said first-named roller for gripping the master sheet for moving it with respect to the drum, an arm pivotally mounted on said drum adapted upon an inward swinging movement to give said first-named roller a rotary movement for bringing a different portion of the gripped master sheet into printing position adjacent to said opening in the drum, yielding means normally holding said arm against inward swinging movement, a cam movably mounted adjacent to said drum adapted when in operative position to cause said arm to swing inwardly upon each revolution of the drum for causing rotation of said first-named roller, and means comprising a lever adapted in one position to hold said cam retracted from operative position and adapted in a changed position to hold said cam in operative position for actuating said arm.

18. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable into and out of pressure relationship to said first-named roller adapted in one position to permit insertion of a master sheet between the rollers and adapted in the other position to cooperate with said first-named roller for gripping the master sheet for moving it with respect to the drum, an arm pivotally mounted on said drum adapted upon an inward swinging movement to give said first-named roller a rotary movement for bringing a different portion of the gripped master sheet into printing position adjacent to said opening in the drum, yielding means normally holding said arm against inward swinging movement, a cam movably mounted adjacent to said drum adapted when in operative position to cause said arm to swing inwardly upon each revolution of the drum for causing rotation of said first-named roller, and means comprising a lever adapted in one position to hold said cam retracted from operative position and adapted to be moved into a past-centers locked position for holding said cam in operative position for actuating said arm.

19. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable into and out of pressure relationship to said first-named roller adapted in one position to permit insertion of a master sheet between the rollers and adapted in the other position to cooperate with said first-

named roller for gripping the master sheet for moving it with respect to the drum, a short arm mounted to swing about the axis of said first-named roller, a gear fixedly connected with said roller, a pawl carried by said arm adapted upon an inward stroke of the arm to give said roller a rotary movement, a second arm swingingly mounted in position adapted by engagement with said first-named arm to give it an inward swinging movement, spring means normally holding said short arm swung outwardly to the limit of its motion, a cam movably mounted adjacent to said drum adapted in operative position to engage said second arm upon each revolution of the drum for causing rotation of said first-named roller, and means comprising a lever pivotally mounted adjacent to the drum adapted in one position to hold said cam retracted from operative position and adapted in a changed position to hold said cam in operative position for actuating said arm, said lever being held automatically in either of its said two positions.

20. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable into and out of pressure relationship to said first-named roller adapted in one position to permit insertion of a master sheet between the rollers and adapted in the other position to cooperate with said first-named roller for gripping the master sheet for moving it with respect to the drum, an arm pivotally mounted on the drum adapted by an operative stroke to move said second roller into outwardly spaced relation to the face of the drum, a cam pivotally mounted adjacent to said drum adapted when in operative position to give said arm an operative stroke at a predetermined point in each revolution of the drum, and a lever for moving said cam into and out of operative position.

21. In a duplicating machine, the combination of a rotatably mounted drum having an opening through its wall along one side thereof, a roller rotatably mounted in said drum opposite to said opening and spaced inwardly a short distance from the face of the drum, a second roller rotatably mounted in position adjacent to said first-named roller and movable into and out of pressure relationship to said first-named roller adapted in one position to permit insertion of a master sheet between the rollers and adapted in the other position to cooperate with said first-named roller for gripping the master sheet for moving it with respect to the drum, gripper means carried by said drum for securing one end of said master sheet releasably in fixed position on the drum, means comprising a pivotally mounted cam adapted when in operative position to cause said grippers to open at a predetermined point in each revolution of the drum, an arm pivotally mounted on the drum adapted by an operative stroke to move said second roller into outwardly spaced relation to the face of the drum, means comprising a second pivotally mounted cam adapted when in operative position to give said arm an operative stroke at a predetermined point in each revolution of the drum, and a lever for moving said cams in timed relation to each other adapted by a stroke in one direction to cause said grippers first to close

for holding a master sheet in position and thereafter to produce a movement of said arm for causing said second roller to move inwardly for pressing an intermediate portion of the master sheet into operative engagement with said first-named roller.

22. In a duplicating machine, the combination of a duplicating drum, means on said drum for securing a master sheet thereto with the sheet wrapped about the outer face of the drum, means carried by said drum engaging an intermediate portion of said master sheet and adapted to feed said intermediate portion into the interior of said drum while the end portions of the master sheet remain on the exterior of said drum, means responsive to rotation of the drum for actuating said feeding means in a step by step manner, and a roller for pressing copy sheets against said master sheet.

23. In a duplicating machine, the combination of a duplicating drum having a cylindrical surface, means on said drum for securing one end of a master sheet to said cylindrical surface with the sheet wrapped about the outer face of the drum, means carried by said drum and engaging said master sheet to feed it into the interior of said drum, and a roller for pressing copy sheets against said master sheet.

24. In a duplicating machine, the combination of a duplicating drum having a cylindrical surface for carrying a master sheet, a curved guard plate carried by the drum and disposed over said master sheet, said guard plate having an aperture therein exposing a portion of said master sheet, means carried by said drum and engage-

able with said master sheet to advance a portion thereof in a step by step manner relative to said aperture, means responsive to rotation of the drum for actuating said advancing means, and a roller for pressing copy sheets against said master sheet.

25. In a duplicating machine, the combination of a drum having an opening at one side, a roller rotatably mounted inside of said drum adjacent to said opening, means engaging a master sheet wrapped about the outer face of the drum for holding it in engagement with said roller so as to be advanced from a position outside of the drum into the drum upon rotation of the roller, and means for giving said roller a step by step rotary movement upon successive revolutions of the drum for bringing different portions of said master sheet into printing position on the face of the drum.

26. In a duplicating machine, the combination of a drum having an opening at one side, a roller rotatably mounted inside of said drum adjacent to said opening, means adapted by engagement with the outer face of a master sheet wrapped about the drum to move the master sheet into engagement with said roller and to hold the master sheet in position against the roller so as to be advanced into the drum by rotation of the roller, and means for giving said roller a step by step rotary movement upon successive revolutions of the drum for bringing different portions of said master sheet into printing position on the face of the drum.

MAURICE R. AVERY.
